UNITED STATES PATENT OFFICE.

HARRY B. WORTHINGTON, OF COLUMBUS, OHIO.

CARD-CASE.

1,086,971.

Specification of Letters Patent.

Patented Feb. 10, 1914.

Application filed May 4, 1912. Serial No. 695,054.

To all whom it may concern:

Be it known that I, HARRY B. WORTHINGTON, a citizen of the United States, residing at Columbus, in the county of Franklin and State of Ohio, have invented a certain new and useful Improvement in Card-Cases, of which the following is a specification.

One form of package for professional, business or visiting cards at present in wide use consists of a folding cover having a clamp and a pack of cards gripped at one end by the clamp, the cards being each perforated across its end so that one or more can be readily torn off when wanted. When such a card is torn off the severed end necessarily presents a serrated, disfigured appearance not altogether pleasing to those who are fastidious as to such matters.

The object of the present invention is to provide a card case in which the cards are preserved in their prime condition and can be removed without any tearing or disfigurement whatever and the invention is embodied in the construction herein specifically shown and described and then pointed out in the claim.

In the accompanying drawings forming part hereof Figure 1 is a plan view of the invention showing the cover spread open a part of the cover being removed. Fig. 2 is a sectional view on the line *x—x* Fig. 1. Fig. 3 is an edge view.

In the views 5 designates the ordinary flexible cover which is foldable after the manner of the cover of a book. Near the middle of the inner side of the cover is secured a metallic frame including a base 6, side walls 7 and end wall 8. On the base is riveted at 9 the arms 10 of a spring frame having a cross bar 10^a. Pivoted at 11 between the side walls 7 is a clamp member 12 having a curved pinching edge 12^a that co-

operates with the cross bar 10^a to grip the end of the package of cards 13. The clamp member 12 is provided with spurs 12^b punched out of the metal of the clamp member 12. The base 6 has portions punched up out of it to form a space or socket into which the spurs 12^b can project when the clamp member 12 is turned down into card clamping position as best shown in Fig. 2. I propose to alternate the cards with slips of tissue paper as seen at 14, said slips being somewhat longer than the cards so as to leave projecting ends through which the spurs 12^b can be thrust when the clamp member 12 is turned down to grip the package of combined cards and slips. The function of the said spurs is to retain the tissue slips when a card is withdrawn. When therefore a card is removed from the package no embarrassment is occasioned by the necessity of disposing of the tissue slip. In use the upper tissue slip or slips are merely turned aside sufficiently to permit the taking of a card between the fingers, the card being then withdrawn without difficulty.

The forms of the parts can be changed without departing from the gist of the invention.

What I claim is:

The combination of a cover, a frame therein containing a spring, a package clamping member to coöperate with said spring, said clamping member provided with a spur, and a package of cards with a protecting slip clamped between the clamping member and spring, the protecting slip being engaged by said spur and retained thereby when a card is removed from the package.

HARRY B. WORTHINGTON.
